UNITED STATES PATENT OFFICE.

CHARLES E. BENHAM, OF SCHENECTADY, NEW YORK, ASSIGNOR TO THE MAQUA COMPANY, A CORPORATION OF NEW YORK.

PRINTER'S FURNITURE.

1,349,257.

Specification of Letters Patent. Patented Aug. 10, 1920.

Application filed May 29, 1920. Serial No. 385,324.

To all whom it may concern:

Be it known that I, CHARLES E. BENHAM, a citizen of the United States, residing at Schenectady, in the county of Schenectady, 5 State of New York, have invented certain new and useful Improvements in Printers' Furniture, of which the following is a specification.

The present invention relates to printers' 10 furniture and has for its object to provide an improved form of apparatus of this character.

For a consideration of what I believe to be novel and my invention, attention is directed to the accompanying description and 15 the claims appended thereto.

In the drawing, the figure is a perspective view of apparatus embodying my invention.

According to my invention, I employ a 20 number of solid blocks 1 made from suitable metal such as steel or cast iron for example, and provide them with slots 2 which extend vertically of the blocks when the blocks are assembled in making a frame. 25 Blocks 1 are finished all over to accurate printers' dimensions and slots 2 are likewise of accurate printers' dimensions as to their width, depth and the distance they are located from the corners of the blocks. Blocks 30 1 may be termed lock quads, and in addition to their use in frames as will appear later they may be employed singly or in groups of various sizes and shapes as quotation quads.

35 To form a rectangular frame as shown in the drawing, the purpose of which is to form a rectangular blank on a printed page, the compositor takes four lock quads and inserts the ends of ordinary printers' slugs 3 in the slots 2, the quads forming the four 40 corners of the frame. Since the lock quads and the slots therein are of accurate printers' dimensions, standard slugs build up frames with them which have exact printers' 45 dimensions as will appear more clearly in connection with the numerical example given hereinafter. The assembled parts form a frame which will hold together due to the snug fitting of the parts and may be handled 50 as a unit. The compositor then fills the spaces outside slugs 3 by means of other ordinary printers' slugs 4 so as to give the frame a continuous, smooth outside surface. This forms a complete piece of printers' 55 furniture of standard printers' dimensions,

which can be handled as a unit and used in the well-known manner.

By my invention a compositor is able to quickly build up printers' furniture of any desired standard size by selecting slugs of 60 the desired lengths, and since every printing establishment is supplied with such slugs as a part of their regular equipment, my invention requires the addition of only a single new type of equipment in addition 65 to that already in use. Furthermore, such new pieces of equipment may be used also as quads. As is well understood, slug material may be purchased in strips and is cut into various standard lengths for use as a 70 part of the equipment of every printing establishment.

It is to be noted that in using my invention it is only necessary to insert the ends of ordinary slugs into the slots 2, a thing 75 which can be quickly done without waste of time, and that there are no clamps, or other type of special securing means required. My invention also may replace standard furniture such as is now in common use. It 80 thus serves to effect a saving both in time and equipment.

As a matter of illustration and in order that my invention may be better understood, I will now give numerical values to the dimensions of the various parts. It is to be understood, however, that this is only by way of illustration and is not to be taken as a limitation of my invention. Each lock quad 1 may be a 48-point em quad of steel, 85 and the two slots 2 may be each 12 points deep, 6 points wide and spaced 12 points from the corner of the blocks. The dimensions are thus all standard printers' dimensions. Any 6-point slug will therefore fit 90 slot 2 and will enter the slot to a depth of exactly 12 points. It will also be exactly 12 points from the corner of the quad. If it is desired to make a frame to fill a space 15 picas by 27 picas, for example, the four 95 quads 1 are assembled with slugs 3 for the sides which are 21 picas long and with slugs 3 for the ends which are 9 picas long. Since the quads 1 are 4 picas square and slots 2 are 12 points, or 1 pica deep, this will give a 100 frame exactly 15 by 27 picas. The spaces outside the sides and ends are then filled in with slugs 4 which for the sides must be 19 picas long and for the ends 7 picas long. Single slugs 12 points in thickness may be 105 110

used for this or two slugs each 6 points in thickness may be used as is obvious. The frame is then complete and ready for use.

As is clear, the lock quads 1 and slots 2 may have any desired dimensions as long as they are standard printers' dimensions to fit in with standard slugs, such as 6-point or 12-point slugs, for example.

In accordance with the provisions of the patent statutes, I have described the principle of operation of my invention, together with the apparatus which I now consider to represent the best embodiment thereof, but I desire it to be understood that the apparatus illustrated is only illustrative and that the invention may be carried out by other means.

What I claim as new and desire to secure by Letters Patent of the United States, is:—

1. A lock quad for use in building printers' furniture comprising a block having standard printers' dimensions provided with slots of standard printers' dimensions adapted to receive standard printers' slugs.

2. In printers' furniture, a frame com-

prising rectangular corner blocks of standard printers' dimensions, said blocks being provided with slots of standard printers' dimensions in width and depth, and slugs having their ends located in said slots.

30

3. In printers' furniture, a frame comprising rectangular corner blocks of standard printers' dimensions, said blocks being provided with slots of standard printers' dimensions in width and depth, said slots being spaced standard distances from the corners of the blocks, slugs having their ends located in said slots, and other slugs located outside said first-named slugs and between said blocks.

35

4. A block for use in connection with printers' slugs for building printers' furniture, said block having standard printers' dimensions and being provided with slots of standard printers' dimensions which slots are spaced standard distances from the corners of the blocks.

40

In witness whereof, I have hereunto set my hand this 28th day of May, 1920.

CHARLES E. BENHAM.
